UNITED STATES PATENT OFFICE

99,874

DESIGN FOR A CABINET FOR DIATHERMY APPARATUS

Robert Jerome Lindquist, Los Angeles, Calif.

Application March 13, 1936, Serial No. 61,620

Term of patent 7 years

To all whom it may concern:

Be it known that I, Robert Jerome Lindquist, a citizen of the United States, residing at Los Angeles, in the county of Los Angeles and State of California, have invented a new, original, and ornamental Design for a Cabinet for Diathermy Apparatus, of which the following is a specification, reference being had to the accompanying drawing, forming part thereof.

Fig. 1 is a front elevational view of the cabinet;
Fig. 2 is a side elevational view thereof;
Fig. 3 is a top plan view; and
Fig. 4 is a fragmentary section taken as indicated on the line 4—4 of Fig. 1.

I claim:

The ornamental design for a cabinet for diathermy apparatus, as shown.

ROBERT JEROME LINDQUIST.
